UNITED STATES PATENT OFFICE.

ISAAC E. PALMER, OF MIDDLETOWN, CONNECTICUT; TOWNSEND PALMER AND NATHALIE T. PALMER ADMINISTRATORS OF SAID ISAAC E. PALMER, DECEASED.

GROMETING-MACHINE.

1,282,714.

Specification of Letters Patent. Patented Oct. 22, 1918.

Application filed July 21, 1914. Serial No. 852,323.

To all whom it may concern:

Be it known that I, ISAAC E. PALMER, a citizen of the United States, and a resident of Middletown, in the county of Middlesex 5 and State of Connecticut, have invented an Improvement in Grometing-Machines, of which the following description, in connection with the accompanying drawings, is a specification, like characters on the drawings representing like parts.

This invention relates to grometing machines which may be of general application, but which are particularly intended for use in applying gromets to gromet holes of cloth, 15 sheets or strips constituting suspension ends or other parts of couch hammocks.

In order that the principle of the invention may be readily understood, I have disclosed a single embodiment thereof in the 20 accompanying drawings, wherein—

Figure 1 is a side elevation of a grometing machine embodying my invention;

Fig. 2 is a transverse vertical section thereof upon the line 2—2 of Fig. 1;

Fig. 3 is a horizontal section upon the line 3—3 of Fig. 1;

Fig. 4 is a side elevation of the head of the grometing machine on an enlarged scale and showing the support in section;

Fig. 5 is a plan view representing a slightly modified form of the invention;

Fig. 6 is a plan view upon an enlarged scale and partially in transverse section of the preferred form of my invention;

Fig. 7 is a vertical section taken through the gromet-applying device and its support;

Fig. 8 is a detail of one of the blank or sheet holders;

Fig. 9 is a plan view of the apparatus and 40 showing the preferred form of blank or sheet-positioning means; and

Fig. 10 is a modification representing a plurality of heads arranged in a gang and adapted for use in applying different sized 45 gromets.

An important object of my invention is to provide in proximity to each other a hole 50 punching device and a gromet applying device which may be independently operated, so that the blanks or sheets may be individually presented in turn thereto conveniently and without lost time or movement. Preferably in conjunction therewith, I provide means for holding a blank or sheet or 55 for holding a series of blanks or sheets in

register, so that the gromets may be applied at the same point to each. Other objects of the invention will be set forth more fully in detail hereafter.

Referring more particularly to the drawings, the framing of the machine is represented most clearly at 1 in Fig. 1, it consisting of suitable uprights at the upper end of which is a suitable top 2 consisting of the basal support for the head 3 of the mechanism. In the rear of the head 3 is positioned a table 4 supported upon legs 5 or otherwise and upon which the blanks or sheets 6 indicated in Fig. 9 are adapted to be piled in register.

Obviously the apparatus is adapted for applying gromets to widely differing devices, but in the disclosed embodiment of the invention I have represented it as peculiarly adapted for applying gromets to the cloth 75 suspension ends of couch hammocks. Such cloth ends are of varying dimensions, but are herein represented as measuring about two feet in each direction. A couch hammock is customarily provided with cloth suspension ends extending transversely of the hammock and with a cloth wind shield extending longitudinally of the hammock and of substantially the same height. The meeting edges of the ends and wind shield are 80 customarily provided with gromets through which lacing cords are passed, thereby detachably securing said edges together. It is important, therefore, that the gromets be

85 applied in the same relative positions in the 90 entire series of suspension ends and of the wind shields, so that when the parts are assembled, each pair of gromets of a suspension end and wind shield may be in horizontal alinement. For this purpose and as more 95 fully set forth hereinafter, I preferably provide suitable means for holding a series of blanks or sheets constituting the suspension ends in register, but in such manner as to permit the manual application thereof singly 100 to the punch and gromet applying devices without disturbing their registering relation.

Referring particularly to Figs. 1 and 4, the head 3 is therein shown as provided 105 with a vertical through-opening 6 receiving therein a plunger 7 having preferably detachably secured to the lower end thereof a punch 8, here shown as having a concaved lower end 9. Surrounding the punch 110

within the opening 6 is a coiled spring 10 tending normally to elevate the punch into the position shown in Fig. 4. Directly below the punch 8 is a die 11 having a socket 12 therein having a surrounding cutting edge at its upper end and with which the surrounding edge of the punch 8 cooperates to punch a suitable sized hole in the blank or sheet presented thereto.

10 Mounted in the same head and in proximity to the punch, and preferably directly in the rear thereof is a suitable gromet applying device. As here represented and as shown most clearly in Figs. 4 and 7, 15 this consists of a socket piece 13, preferably of metal, and having an axial socket 14 of suitable depth therein. The said socket piece 13 is adapted to be reciprocated within the base portion 15 of the head, and for that 20 purpose, it is mounted in a through-opening 16 therein having a notched, upper end 17, thereby presenting a shoulder 18 upon which the socket piece rests when in lowered position. Directly above the socket piece 13 25 and secured to an overhanging portion 19 of the head 3 is a co-acting member 20 of the gromet applying device. Said member is provided with a preferably cylindrical projection 21, which is adapted to enter the 30 socket 14 of the socket piece 13 when the latter is lifted. The upper face 22 of the socket piece may be and is represented as annularly grooved or recessed at 23 to receive the lower member 24 of the gromet. 35 Said member 24 is provided with an up-standing neck 25 which is adapted to be upset on the overlying member 26 of the gromet in the action of the gromet applying mechanism, thereby to secure the gromet 40 in the hole punched in the blank or sheet by the punch and die 8, 11.

While I may operate the punch 8 and the gromet applying device 13 in any suitable manner, I have, in the disclosed embodiment 45 of the invention, represented the punch 8 as mounted in the overhanging portion of the head, so as to be moved downward in the punching operation, and have represented the socket piece 13 as mounted in the basal 50 portion 5 of the head, so that it may be elevated in the gromet applying movement. While this position of the parts may be reversed, the construction shown is that preferred.

55 In order to operate the punch and gromet applying device, I may employ any suitable means, but herein I have represented for operating the punch 8 a lever 27 pivoted at 28 in ears or upstanding projections 29 60 extending from the head 3. The lever at its under side is suitably shaped to engage the head of the plunger 7 of the die, so as to depress the same within the opening 6 in the head against the action of the coiled 65 spring 10.

At a suitable point in the frame and preferably near the floor, I mount a rod or shaft-like member 29', shown most clearly in Figs. 1 and 3. Thereon I pivotally mount a treadle 30 having a hub 31 suitably received upon said rod 29. Connecting the treadle 30 and lever 27 is a suitable link or connecting rod 32, and preferably I provide a coiled spring 33 connected to the supporting rod 29 and the hub of the treadle 75 30, so as to assist the coil spring 10 in lifting the lever 27 after each punching movement.

The socket piece 13 has an integral or suitably attached portion 34 extending through the opening 16, and here shown 80 as having an enlargement 35 provided with a transverse socket or opening 36 adapted loosely to receive one end 37 of a lever 38 pivoted at 39 in a suitable bracket 40 upon the under side of the basal support 2 of 85 the head. The opposite arm 41 of said lever is connected by a rod or link 42 to a treadle 43 likewise suitably mounted upon the rod or support 29' as indicated most clearly in Fig. 3. Through the instrumentality of 90 the treadle 43 the socket piece 13 is lifted to secure the gromet pieces 24, 26 in position upon the blank or sheet. The parts are of sufficient weight so that the socket piece is promptly returned to inactive position after 95 the application of the gromet, but preferably I provide a coiled spring 44 suitably connected by a strap 45 or otherwise to the enlargement 35 of the socket piece and also to the frame 1 at any suitable point. 100

As previously indicated, I preferably provide means whereby a blank or sheet may be held or whereby a series of blanks or sheets may be held in register and in such manner that they may be individually presented one 105 after another first to the action of the punch and then to the action of the gromet applying device without withdrawing the blank or sheet from its support, and thus without removing it from registering position. For this purpose, I preferably provide suitable holding devices to which the front edges of the blanks or sheets are applied at relatively great distance apart, so that the operative may seize the blank or sheet by its forward edge and, without withdrawing it from the holding device, may move it into position beneath the punch 8 and then into position over the gromet 110 applying device 13. To this end, it is of great importance that the punch and gromet applying device be in proximity to each other, and in order to secure the best results, the said members should be in alignment longitudinally of the head. They are 115 thus in a line which is normal to the front or transversely extending edges of the blanks or sheets.

While any suitable means may be employed to hold the blanks or sheets and to 120 125 130

permit them to be individually presented as described, I have in Figs. 1, 2, 6 and 9 represented one form of means for this purpose. Therein I have represented blank 5 shifting means here consisting of a sprocket chain 46 mounted upon horizontally alined sprocket wheels 47, 48, themselves mounted for rotation upon suitable brackets 49, 50 laterally projecting from the machine frame 10 1 in such manner that the upper and lower runs of said sprocket chain are horizontal. The said chain is provided with a preferably metallic strip 47' secured at its intermediate portion 48' to the upper face of the 15 chain and bent upwardly at points 49', 50' between its ends, so that the end portions 51, 52 are spaced somewhat above the chain 46. At suitable points, and as shown in Fig. 9, the strip 47 is longitudinally slotted 20 as indicated at 53, 54 for the reception of clips or holders 55, 56 represented upon a larger scale in Fig. 8. The said clips or holders are held in position in said slots 53, 54 by means of bolts 57, and may be 25 adjusted to any suitable position therein.

The forward edges of the blank or sheets are adapted to be positioned in said clips or holders, and in order to move the same, so that the proper portion thereof may be presented to the action of the punch or gromet applying device, I provide the sprocket chain 46 with suitable means to hold it in the position to which it is shifted and to determine accurately such position. For that 30 purpose, I have in Fig. 9 represented the chain as having pivoted thereto in ears 58 blade-like levers 59, which when turned forward and downwardly are adapted to be received in any suitable notches or slots 35 60 in a longitudinal strip 61, which is positioned edgewise in and projects above the upper surface of the adjacent portion 61 of the bed of the machine at each side of the head 3 thereof. The said notches or 40 45 slots 60 are symmetrically arranged upon opposite sides of the head 3.

The sprocket wheels 47, 48 are positioned apart preferably the entire width of the table 4, and the construction is such that 50 when the operative after having elevated the levers 59, has shifted the sprocket chain 46 in one direction or the other until the said levers are permitted to drop into the proper slots or notches, the entire series of 55 blanks or sheets is supported in proper position with respect to the head 3. After each blank or sheet 6' has been grometed as described, it is withdrawn from the holders 55, 56 and the next underlying blank 60 or sheet is treated in the same manner. The sprocket chain is flexed transversely by the operator in moving a blank or sheet toward or from the punch and gromet applying device. Within the scope of the invention, 65 a single blank or sheet may be supported at

a time within the holders 55, 56 and moved as described not only transversely of the head, but also in a direction axially or longitudinally thereof. Also within the scope of the invention, a series of blanks or sheets 70 may be so supported, and in such case in order to punch a single blank or sheet and to apply the gromet thereto, the operator preferably manually moves the blank or sheet without withdrawing it from the holders 55, 56, and may at the same time manually displace portions of the overlying blanks or sheets. If desired, the entire series of blanks or sheets may be so supported in the holders 55, 56, and the latter may be 75 so located that it is necessary for the operator to draw or move each of the series of sheets or blanks within operative relation to the punch and gromet applying device.

In Fig. 5, I have shown a slightly modified form of the shifting means for the sheets or blanks. Instead of providing a strip 60, such as shown in Fig. 9, I provide a short adjustable strip 62 provided with a longitudinal slot 63 to receive a bolt or 80 screw 64 by which it may be secured in proper adjusted position. Upon the strip 63, I pivot at 65 a lever 66 having an upstanding stud or pin 67, which, when it is swung into the position shown in Fig. 5, 85 90 constitutes a stop against which the lever 59 is adapted to be received, thereby to hold the series of blanks or sheets in shifted position.

In Fig. 10, I have represented a slightly 100 modified form of my invention, wherein I have shown three heads 3^a, 3^b, 3^c which are designed to contain punches and gromet applying devices of graduated size. For example, the punch and gromet applying 105 device of the head 3^a may be the smallest of the series, those of the head 3^b may be of an intermediate size and those of the head 3^c may be of the largest size. The heads are arranged substantially as shown, so that their 110 inner ends are brought close together, and but slight movement of the blank or sheet is necessary to present it to the desired head. I have therein indicated diagrammatically the punches 9 and socket pieces 13. It will 115 be observed that these are arranged in parallel lines, and that those of the outermost heads are not arranged axially of the heads. Each of the punches and gromet applying devices of these heads is independently operated, and preferably in the manner heretofore described with respect to the head 3.

From the foregoing description, it will be evident that I have provided a simple and easily operated apparatus, by which 120 sheets of any desired character may have holes punched therein and gromets applied to such holes at the proper points and that the entire series of sheets are uniformly 125 acted upon.

It is not essential to the operation of my invention that a sheet shifting means be employed, inasmuch as within the scope of my invention, the operative may grasp a sheet 5 lying loosely upon the table 4 and apply it to the punch and gromet applying devices of the head. In such case, the sheet is customarily marked at the points where the holes are to be punched therein. Preferably, however, I provide suitable holding 10 means whereby an entire series of blanks or sheets may be held in close proximity to the head, and so that they may be operated upon without disturbing their relation with 15 respect to the other members of the series.

Having thus described one illustrative embodiment of my invention, I desire it to be understood that although specific terms are employed, they are used in a generic 20 and descriptive sense and not for purposes of limitation, the scope of the invention being set forth in the following claims.

Claims:

1. A grometing machine comprising in 25 combination, a head having a punch and a gromet applying device positioned therein in proximity to each other, a manually movable support for one or more sheets or blanks adapted to be presented manually to 30 said punch and gromet, said support being movable transversely of said punch and gromet and also being movable toward and from said punch and gromet in a line substantially at right angles to that of its trans- 35 verse movement.

2. A grometing machine comprising in combination, a head having a punch and a gromet applying device positioned therein in proximity to each other, a support for 40 one or more sheets or blanks, and means for permitting movement of said support transversely to said punch and gromet applying device, said support being yieldable in a direction toward and from said punch and 45 gromet applying device in a direction substantially at right angles to its transverse movement.

3. A grometing machine comprising in combination, a head having a punch and a 50 gromet applying device in proximity to each other, a movable support for one or more sheets or blanks, and means whereby said support may be moved with said sheets or blanks in either of two directions substantially normal to each other.

4. A grometing machine comprising in combination, a head having a punch and a gromet applying device mounted therein in proximity to each other, a guiding belt-like 60 member, supporting means therefor, and means on said member detachably to support the sheets or blanks for presentation to the punch and gromet applying device, said member being adapted to be moved by

the operator toward or from the punch and 65 gromet applying device.

5. A grometing machine comprising in combination, a head having a punch and a gromet applying device positioned therein in proximity to each other, and a flexible 70 support for one or more sheets or blanks, said support being adapted to be flexed with its supported blanks or sheets toward and from said punch and gromet applying device. 75

6. A grometing machine comprising in combination, a head having a punch and a gromet applying device positioned therein in proximity to each other, and a belt like, flexible support for one or more sheets or 80 blanks located in proximity to said punch and gromet applying device and adapted to be flexed toward and from the punch and gromet applying device with the supported blanks or sheets. 85

7. A grometing machine comprising in combination, a head having a punch and a gromet applying device positioned therein in proximity to each other, independently operable means therefor including means 90 to depress one of said members and to lift the other in effecting their operation, and a manually movable support for blanks or sheets located in proximity to said punch and gromet applying device and adapted 95 to be moved with a supported blank or sheet in a direction along said head from the punch to the gromet applying device.

8. A grometing machine comprising in combination, a head having a punch and a 100 gromet applying device positioned therein in proximity to each other, independently operable means therefor including means to depress one of said members and to lift the other in effecting their operation, and a 105 manually movable support for blanks or sheets located in proximity to said punch and gromet applying device, said support being movable in two directions substantially normal to each other together with 110 the supported blanks or sheets.

9. A grometing machine comprising in combination, a head having a punch and a gromet applying device mounted therein in proximity to each other, independent 115 means for operating said punch and gromet applying device, and manually controlled and manually movable means to hold one or more blanks in position adjacent thereto and so that each member of said series may 120 be manually applied to said punch and to said gromet applying device.

10. A grometing machine comprising in combination, a head having a punch and a gromet applying device mounted therein in 125 proximity, means to depress the punch, means to lift the gromet applying device to effect the operation thereof, and a flexible

support for a series of blanks or sheets located in proximity to said punch and gromet applying device and adapted to be flexed toward the same together with the 5 said blanks or sheets.

11. A grometing machine comprising in combination, a head having a punch and a gromet applying device mounted therein in proximity, means to depress the punch, 10 means to lift the gromet applying device to effect the operation thereof and manually controlled and manually movable means to hold a series of blanks in position adjacent thereto and so that each member of said 15 series may be manually applied to said punch and to said gromet applying device said holding means being movable transversely and also longitudinally of said head.

12. A grometing machine comprising in 20 combination, a head having a punch and a gromet applying device mounted therein in proximity, means to depress the punch, means to lift the gromet applying device to effect the operation thereof, means for independently operating said punch and 25 gromet applying device, and a belt-like support for sheets and blanks located in proximity to said punch and gromet applying device and adapted to be moved toward the 30 same.

13. A grometing machine comprising in combination, a head having a punch and a gromet applying device mounted therein in proximity, and a support for sheets or blanks 35 adapted to be moved with said sheets or blanks toward said punch and gromet applying device, and also adapted to be moved in a direction substantially normal to the direction of the first mentioned movement.

40 14. A gromet machine comprising in combination, a head having a punch and a gromet applying device mounted therein in proximity to each other, means for operating said parts, a guiding belt-like member, supporting means therefor, and means on said member to hold the sheets or blanks whereby one or more blanks or sheets while so held may be shifted laterally of the punch and of the gromet applying device.

50 15. A grometing machine comprising in combination, a head having a punch and a gromet applying device mounted therein in proximity, means to depress the punch, means to lift the gromet applying device to 55 effect the operation thereof, means to hold a series of blanks or sheets in register and manually controlled and manually operable belt means to shift said series laterally of the punch and gromet applying device while 60 still maintaining them in register.

16. A grometing machine comprising in combination, a head having a punch and a gromet applying device mounted therein in proximity to each other, a guiding belt-like

member, supporting rotatable means therefor 65 and means on said member detachably to support the sheets or blanks for presentation to the punch and gromet applying device.

17. A grometing machine comprising in combination, a head having a punch and a gromet applying device mounted therein in proximity to each other, independent means for operating said punch and gromet applying device, a guiding sprocket chain, supporting sprocket gears therefor, and means on said chain to hold the blanks or sheets whereby one or more blanks or sheets while so held may be shifted laterally of the punch and of the gromet applying device.

18. A grometing machine comprising in 80 combination, a head having a punch and a gromet applying device mounted therein in substantial alinement longitudinally of the head, independent means for operating said punch and gromet applying device, a guiding sprocket chain, supporting sprocket gears therefor, and means on said chain to hold the blanks or sheets whereby one or more blanks or sheets while so held may be shifted laterally of the punch and of the 90 gromet applying device.

19. A grometing machine comprising in combination, a head having a punch and a gromet applying device mounted therein in proximity, means to depress the punch, 95 means to lift the gromet applying device to effect the operation thereof, a guiding sprocket chain, supporting sprocket gears therefor, and means on said chain to hold the blanks or sheets whereby one or more 100 blanks or sheets while so held may be shifted laterally of the punch and of the gromet applying device.

20. A grometing machine comprising in combination, a head having a punch and a 105 gromet applying device mounted therein in proximity, independent treadle mechanism to operate the same, a guiding sprocket chain, supporting sprocket gears thereon, and means on said chain to hold the blanks 110 or sheets whereby one or more blanks or sheets while so held may be shifted laterally of the punch and of the gromet applying device.

21. A grometing machine comprising in 115 combination, a head having a punch and a gromet applying device mounted therein in proximity to each other, independent means for operating said punch and gromet applying device, means to hold a series of 120 blanks or sheets in register, means to shift said series laterally of the punch and gromet applying device while still maintaining them in register, and movable latches carried by said sheet or blank holding means to 125 hold said shifting means in each of a series of positions into which it may be moved, and means whereby blanks or sheets may be

moved with their holding means toward the punch and gromet applying devices.

22. A grometing machine comprising in combination, a head having a punch and a gromet applying device mounted therein in substantial alinement longitudinally of the head, independent means for operating said punch and gromet applying devices, means to hold a series of blanks or sheets in register, means to shift said series laterally of the punch and gromet applying device while still maintaining them in register, and levers mounted upon said sheet or blank holding means to hold said shifting means in each of a series of positions into which it may be moved, and means whereby blanks or sheets may be moved with their holding means toward the punch and gromet applying devices.

23. A grometing machine comprising in combination, a head having a punch and a gromet applying device mounted therein in proximity, means to depress the punch, means to lift the gromet applying device to effect the operation thereof, means to hold a series of blanks or sheets in register, means to shift said series laterally of the punch and gromet applying device while still maintaining them in register, means to hold said shifting means in each of a series of positions into which it may be moved, and means whereby blanks or sheets may be moved with their holding means toward the punch and gromet applying devices.

24. A grometing machine for applying gromets to the edge portion of a sheet, com-

prising in combination, a single head, a punch and a gromet applying device, each mounted for vertical reciprocation therein and positioned one directly in advance of the other substantially normal to the edge of the sheet in proximity to which the gromet or gromets are applied, so that flexible, sheet-like blanks held at a plurality of widely spaced points may be readily flexed between said holding points and be brought successively into operative position with respect to the punch and the gromet applying device, and independent manually operable means for said punch device and for said gromet applying device.

25. A grometing machine comprising in combination, a head having a punch and a gromet applying device vertically reciprocable therein, a punch operating lever mounted above the punch in position to engage the same, a gromet applying device operating lever mounted below the head and adapted to operate said device, independently mounted treadles for said levers, operating connections between said levers and treadles respectively, and a belt-like support for a sheet or blank to be presented to the punch and gromet applying device.

In testimony whereof, I have signed my name to this specification, in the presence of two subscribing witnesses.

ISAAC E. PALMER.
